UNITED STATES PATENT OFFICE.

WILLIAM F. MORGAN, OF OSWEGO, NEW YORK, ASSIGNOR TO AMES IRON-WORKS, OF SAME PLACE.

IMPROVEMENT IN DOORS FOR FEEDING STRAW TO FURNACES.

Specification forming part of Letters Patent No. **159,524**, dated February 9, 1875; application filed January 15, 1875.

To all whom it may concern:

Be it known that I, WILLIAM F. MORGAN, of the city of Oswego, in Oswego county, State of New York, have invented an Improvement in Doors for the Fire-Places of Steam-Boilers, of which the following is a specification, reference being had to the accompanying drawings, forming part thereof.

Figure 1 is a front view of my improved doors, and Fig. 2, a plan of the same, showing particularly the levers and handle by which the doors are opened and shut.

My improved doors are specially designed and adapted for the use of straw as a fuel for steam-boilers; and my invention consists in the peculiar construction and combination, with the doors, of certain levers or arms and a sliding rod, hereinafter described.

A A' represent the doors, and B the frame in which the doors are set. C and C' are revolving posts, to which the doors are attached, and upon which they swing as on hinges, the said posts having their bearings in the top and bottom plates, a b, of the frame B. The upper ends of the said posts extend through the upper plate, a, of the frame B, and on them, respectively, are attached the arms or levers D D'. E is a rod, arranged to slide in the supports d d', secured upon the upper face of the plate a. Secured on this rod is a cross-bar, F, and G G' are links, jointed respectively to the opposite ends of this cross-bar and the free ends of the arms D D'. The doors, being of equal width, and severally wider than half the space between the posts C C', meet in the center of said space when closed, at an angle of about forty-five degrees, as shown by dotted lines e e' in Fig. 2, and swing inward back against the side walls of the frame B when open, as shown by the dotted lines f f'.

It is evident that when the handle or rod E is drawn out, the cross-bar F, the links G G', and arms D D', as shown by the full lines in Fig. 2, will act to close the doors, and that, from this position, the doors may be swung open inward, either by pressure directly against the doors themselves, or by pushing

the rod E in, into the position shown by dotted lines in Fig. 2.

These doors, with their frame, and the other devices described, are fixed in the front of the fire-place of a steam-boiler. They are specially designed for use on boilers of engines employed as motors for thrashing-machines in which straw is used as fuel. Such engines are necessarily operated surrounded by quantities of material highly combustible, and it is very important that every possible safeguard should be provided against the danger of communicating fire to this material in the act of supplying fuel to the boiler. When straw is employed as fuel this danger is very great when the fire-fronts and doors of ordinary construction are used; but it is almost entirely obviated by the use of doors constructed and operated as above described.

The straw is laid in the mouth of the frame while the doors remain closed, and then the doors are opened by pushing the straw directly against them, and after the straw is all securely carried into the fire-place, the fireman conveniently closes the doors by merely pulling out the rod E, without danger of the burning straw escaping out of the doorway.

The devices shown and described—namely, the rod E, cross-bar F, links G G', arms D D', and revolving posts C C'—constitute a cheap, easily-constructed, durable, and conveniently-operated mechanism for opening and closing the doors, and it is to these devices, in connection with the doors and frame, that I limit my claim.

What I claim as my invention, and desire to secure by Letters Patent, is—

The combination, in connection with the frame B, of the doors A A', posts C C', arms D D', links G G', and rod E, substantially as and for the purposes described.

In witness I have hereunto set my hand this 11th day of January, 1875.

WILLIAM F. MORGAN.
